[57] CLAIM

The ornamental design for a spray container, as shown
as described.

DESCRIPTION

FIG. 1 is a front and left side perspective view of a
spray container showing my new design;

FIG. 2 is a rear and left side perspective view thereof;

FIG. 3 is a front elevational view thereof;

FIG. 4 is a side elevational view thereof, the undis-
closed opposite side being a mirror image;

FIG. 5 is a top plan view thereof; and,

FIG. 6 is a bottom plan view thereof.

FIG. 1

FIG. 2

FIG. 3

FIG. 4

FIG. 5

FIG. 6
